UNITED STATES PATENT OFFICE.

FELIX SAMSON, OF NEW YORK, N. Y.

DESIGN FOR NAP-SURFACE OF CLOTHS.

SPECIFICATION forming part of Design No. 12,176, dated February 15, 1881.

Application filed January 21, 1881. Term of patent 7 years.

To all whom it may concern:

Be it known that I, FELIX SAMSON, of New York city, State of New York, have originated a novel Design for the Nap-Surface of Cloths, 5 of which the following is a full, clear, and exact description, in connection with the accompanying drawings.

My design relates to that class of designs which are produced by cutting positive grooves 10 in the pile or face of the cloth, so as to form figures appearing in sharp relief on the wearing-face of the cloth; and my design consists in a certain arrangement and combination of such grooves so as to produce a novel ornamental 15 effect on the face of the cloth, as hereinafter fully set forth.

My design is fully illustrated in the drawings, in which Figure 1 gives a face view of a piece of cloth finished according to my de- 20 sign, and Fig. 2 a cross-section thereof.

The drawings herewith submitted show the design slightly enlarged from what I intend to use—say about one-third more—but my design is not, of course, limited to any definite size. 25 The design illustrated is, however, more especially intended for thick, heavy, or beaver cloths for overcoatings, having a thick surface pile or nap; but the design may, of course, be used on a smaller scale for lighter and finer 30 cloths, if desired.

The general or extreme surface of the cloth is finished practically smooth, as shown; but into this surface are cut positive sharp grooves or channels *a b c*, which produce the appearance of figures in distinct or sharp relief on 35 the nap or wearing-face of the cloth.

It will be seen that according to my design

the relative arrangement and combination of grooves is peculiar. Thus, vertical grooves *a* 40 *b* extend uniformly along the cloth, and a certain number of these grooves are crossed by horizontal grooves *c*, leaving, however, two or more grooves at intervals which are not crossed by the horizontal grooves, thus producing the effect of broad parallel bands of squares or 45 blocks, alternating with a narrow stripe or narrow bands of stripes. The band of squares may, however, be narrower than the band of stripes; but the reverse is preferable, as shown in the drawings. Hence, as the extreme or 50 general surface of the cloth is practically smooth, and as the figures thereon are produced by cutting sharply-defined grooves into the surface, the ornamental figurings thus appear in distinct relief; and as these figures consist of bands of squares combined with stripes, or bands of stripes, the ornamental effect is 55 diverse and strong, and its character novel, lively, and agreeable.

It may be understood that this figuring or 60 finish of the cloth is produced by shearing in the usual way, the shears being, of course, specially formed to produce this design.

What I claim is—

The described design for the nap-surface of 65 cloth, consisting of a series of grooves cut into the pile of the cloth and disposed to form bands of squares alternating with stripes or bands of stripes, substantially as herein illustrated.

FELIX SAMSON.
